UNITED STATES PATENT OFFICE.

AUSTIN H. REEVES, OF NEWARK, NEW JERSEY.

CONCRETE COLUMN.

Application filed February 16, 1923. Serial No. 619,470.

To all whom it may concern:

Be it known that I, AUSTIN H. REEVES, a citizen of the United States, and a resident of Newark, in the county of Essex and 5 State of New Jersey, have invented a new and Improved Concrete Column, of which the following is a full, clear, and exact description.

This invention relates to concrete structures and particularly to an improved concrete column and has for an object to provide a construction wherein the stresses on the column are distributed evenly throughout.

15 Another object of the invention is to provide a concrete column wherein the reinforcing members are arranged in a horizontal or substantially horizontal position.

A further object of the invention is to 20 provide a concrete column wherein the reinforcing members are arranged in groups with the parts thereof extending radially in horizontal planes.

25 A further object is to provide a concrete column in which the reinforcing members take up or reduce the lateral tensile stresses in such a way as to insure the column against failure by lateral stresses.

A still further object of the invention is 30 to make use of the total cross sectional area of the column available for supporting a load.

In the accompanying drawing—

Figure 1 is a longitudinal vertical section 35 through a column disclosing an embodiment of the invention.

Figure 2 is a sectional view through Figure 1 approximately on line 2—2.

In the construction of columns heretofore, 40 reinforcing means have been provided which were designed with the intention of assisting the concrete in supporting the load, by taking up the compression strain. In forming columns of the kind just mentioned, numerous vertical reinforcing structures were provided either of a substantially built up nature or of separate vertical bars. Tests of columns thus reinforced show that for a given size column a plain 45 concrete column supports as great a load as a column reinforced by vertical bars with lateral ties. The reason why such a reinforced column cannot support more load is because the introduction of the vertical bars tends to destroy the even distribution of 50 direct stress by localizing it around the

bars. When a column is loaded so that a certain direct compression stress is present, it has been found by test that there is a corresponding lateral tensile stress. To 60 take care of this lateral tensile stress as well as to overcome certain weaknesses, mats or spiders have been placed in the column shown in the accompanying drawing.

In this construction, a column 1 of concrete round in cross section has been shown, though other shapes could be provided without in any way departing from the spirit of the invention. In order to provide proper reinforcements for taking care of the different stresses in the column and particularly the lateral tensile stresses, a number of mats or spiders 2 are arranged in the column at suitable distances apart. These spaced groups of reinforcing members are arranged substantially as shown in Figure 2, namely, as radiating bars and reinforcing structures connected together in some desirable manner. In Figure 2, eight bars have been shown, though a greater or less number 80 might be used, these bars being connected together at the center in any suitable manner, as for instance, by a ring 3 and intermediate their ends are connected by suitable spacing and tying wires 4 and 5. The outer 85 ends of each of the bars or radiating members 6 is provided with an eye 7 or some other formation, though if desired, it could be merely cut off straight. In the accompanying drawing, radial bars have been 90 shown but it is realized that mats may be made up of other arrangements of bars and placed in a column in a substantially horizontal position without departing from the spirit of the invention. The spiders or mats 95 2 could be dropped into position from the top with little difficulty whenever desired.

For instance, in building the column 1, a suitable foundation or base 8 of any desired kind is provided which is preferably provided with anchoring bars 9 of any desired size, number and shape. These anchoring bars 9 extend a short distance upwardly above the base 8 so that the lower part of the column 1 receives projecting portions. 100 After the column 1 has been built up a short distance, the first spider is dropped into position and then the column is built up a short distance further and a second spider is dropped into position. This action is continued until the full height of the column 110 is provided. The superimposed or support-

- ed structure 10 may be connected with the column 1 in any suitable manner, as for instance, by anchoring rods 11 similar to the rods 9. The spiders or mats 2 are preferably comparatively numerous in the column so that all parts of the concrete formation will be affected thereby and may transmit strains thereto before the strains become excessive.
- 10 It will be noted that in this form of the invention reinforcing arms are provided and distributed through the concrete to readily distribute or take up the lateral tensile stresses as they are formed and before they become excessive at any one point. The reinforcing structure may be hung up first and then the concrete poured around the same though it could be made into sections and fitted into position as the column is built.
- 15 20 By arranging the spiders or mats 2 as specified a structure is presented which resists to

a maximum any compressive shearing or diagonal strain as well as any lateral tensile strain.

What I claim is:—

1. A concrete column, comprising a concrete body having reinforcing members disposed horizontally and in spaced relation to one another throughout the height of the column, each reinforcing member consisting of a ring having a plurality of radial arms terminating in eyes, and wires connecting the several arms together. 25

2. A concrete column, comprising a concrete body having reinforcing members disposed horizontally in spaced relation to one another throughout the height of the column, each reinforcing member comprising a ring having a plurality of radial arms and wires connecting the arms together. 35

AUSTIN H. REEVES.
